Watson E. Coleman ATTORNEY.

UNITED STATES PATENT OFFICE.

ROBERT ULYSSES DAY, OF STEPHENSON, MISSISSIPPI.

NECKTIE HOLDER AND COLLAR CONNECTER.

1,403,741.

Specification of Letters Patent. Patented Jan. 17, 1922.

Application filed January 26, 1921. Serial No. 440,119.

To all whom it may concern:

Be it known that ROBERT U. DAY, a citizen of the United States, residing at Stephenson, in the county of Wilkinson and State of Mississippi, has invented certain new and useful Improvements in Necktie Holders and Collar Connecters, of which the following is a specification, reference being had to the accompanying drawings.

10 This invention relates to necktie and collar holders, and particularly to a holder of this character capable of holding a four-in-hand or bow tie in a natural position without requiring the tie to be extended around the neck or between the folds of the collar.

15 Another object of the invention is to provide a device of this character wherein the tie holding means also serves to connect the ends of the collar so that upon disengagement of the tie holder the collar will be opened or unfastened.

20 A still further object of the invention is to provide a tie holder of this character including novel means for not only maintaining the holder in engagement with the collar but wherein said means prevents separation of the ends of the collar.

25 A still further object of the invention is to provide a tie holder of this character which eliminates wear to neckwear as the tie is only engaged with a small portion of the holder and the danger of permanent creases or damage such as tearing is eliminated.

30 With the above and other objects in view, the invention consists in the improved construction and arrangement of parts to be hereinafter more particularly described, fully claimed and illustrated in the accompanying drawings, in which:

35 Figure 1 is a plan view of a collar with the pockets applied,

40 Figure 2 is a vertical elevation and sectional view of the tie holder and collar connector,

45 Figure 3 is a fragmentary elevation showing the manner of connecting the collar to the shirt, and

50 Figure 4 is an enlarged detail view of the collar connector and tie holder applied to the collar.

55 Referring to the drawings, A designates a shirt including a neckband B, each of the button holes of which are adapted to receive a collar button D whereby each end of the collar 5 is connected to the neckband,

the button hole 6 of the collar being adapted to receive one of the collar buttons while the button hole 7 is adapted to receive the remaining collar button, the usual button hole 8 being provided at the rear portion of the collar for connection to the neckband B. From this arrangement it will be readily seen that the ends 9 and 10 of the collar are not connected to each other, but are connected to the neck band independently of each other.

In order to connect the ends of the collars to each other and permit the collar to be readily unfastened without disengaging the collar from the collar buttons, there is provided a novel combined collar and necktie holder comprising pockets 11 and 12, each pocket consisting of a sheet of material such as used in the construction of the collar, said material being secured by stitching 13 to the outer surface of the inner fold 14. One end of the pocket is substantially oval shaped while the other end is provided with a tab 15 which facilitates the application of the device to the collar. The stitching is extended from the entrance 16 of the pocket around the same, to the opposite end of the entrance and then extended upwardly as at 17 so as to partially close the lower portion of the entrance to the pocket and thereby form a stop, the purpose of which will be hereinafter described. It is of course obvious that these pockets are concealed beneath the folds of the collar, while the tabs 15 are concealed by the tie.

In connection with the pockets, a novel holder is used, said holder consisting of a length 18 of resilient material having its end portions 19 substantially coiled back upon said length and toward each other. The extremity of each of the end portions is extended at right angles to the end portion 19 of the length, and then in parallel relation to provide a stop 20 and a finger piece 21. The intermediate portion 22 of the length is crimped and provided with a fabric covering 23 with which the necktie 25 is engaged, the crimped portion 23 preventing longitudinal movement of the tie 105 with respect to the holder 18. The intermediate portion of the length 18 is also bowed outwardly to conform to the contour of the collar, the end portions being similarly bowed.

110 In the application of the device, the collar 5 as previously stated, is secured to the neck

band without overlapping or connecting the ends of the collar to the neck band by the same means. In order to fasten the collar and maintain the same in the proper position, the holder is inserted beneath the folds of the collar and into the pockets 11 and 12 by first compressing one end portion of the holder through the medium of the finger piece 21 and grasping one of the tabs 15 so as to hold the collar in position. Each end portion of the holder is inserted in this manner into one of the pockets. After the finger pieces 21 have been released the resiliency of the holder urges the stops 20 into engagement with the stops formed by the closed portion of the entrance 16 or stops formed at 17. This causes the ends of the collar to be drawn toward each other and maintained in a natural position. The finger pieces 21 as shown in Figure 3 are concealed by the necktie.

If desired, the necktie may be removed and the collar unfastened simultaneously by simply compressing the holder through the medium of the finger pieces 21. This disengages the stops 20 from the stops of the pockets, permits removal of the holder and separation of the ends of the collar.

From the foregoing it will be readily seen that this invention provides a novel combined collar and tie holder capable of being applied to the various forms of collars and not only permits the collar to be readily fastened and unfastened but lengthens the life of the collar by preserving the button holes from wear, as the button holes are only used to hold the collar in connection with the neckband. In addition to this the invention may be incorporated in any collar without altering the collar in any manner.

What is claimed is:—

1. A tie holder of the character described comprising a collar having a pocket carried by each end portion thereof, and a resilient

member disposed in said pockets and urging 45 said end portions toward each other.

2. A collar connector and tie holder comprising a collar and a shirt neck band, said collar having each end connected to one of the ends of said shirt neckband independently of the adjacent end of the collar and the neckband, a pocket carried by each end portion of the collar, and a tie holding member engaged with the pockets, said member being arranged to urge the ends of the collar 55 toward each other independently of the means holding the collar in connection with the neckband.

3. A collar connector and tie holder comprising a collar and a shirt neck band, said collar having each end connected to one of the ends of said shirt neckband independently of the opposite end of the collar and neckband, a pocket carried by each end of the collar, the entrance to each pocket being 60 disposed adjacent the end of the collar, a resilient connecting member and tie holder having its end portion disposed within the pockets, said end portion being adapted to engage a portion of the pocket to urge the 65 ends of the collar in opposite directions.

4. A collar connector and tie holder comprising a collar having a pocket disposed between the folds of the collar adjacent each end thereof, each pocket having a portion of its entrance closed to form a stop, a length of resilient material having its end portions extended back upon said length toward each other, the extremity of each end portion being formed into a stop adapted to engage 70 the stops to the pocket, whereby the ends of the collars are urged toward and beyond each other through the resiliency of said length.

In testimony whereof I hereunto affix my 85 signature.

ROBERT ULYSSES DAY.
